DESIGN FOR A WRENCH CASE

John Northcott, Toronto, Ontario, Canada

Application March 6, 1942, Serial No. 106,099
In Canada January 29, 1942

Term of patent 14 years

To all whom it may concern:

Be it known that I, John Northcott, a subject of the King of Great Britain, residing at 690 Ontario Street, in the city of Toronto, Province of Ontario, Dominion of Canada, have invented a new, original, and ornamental Design for a Wrench Case, of which the following is a specification, reference being had to the accompanying drawing, forming part thereof.

In the drawing,

Figure 1 is a plan view of the internal side of a wrench case showing my new design in open position;

Figure 2 is a plan view of the external side thereof in open position; and

Figure 3 is a perspective view thereof in closed position.

The characteristic features of the wrench case design disclosed reside in the specific configuration shown in Figs. 1 and 2.

I claim:

The ornamental design for a wrench case, as shown and described.

JOHN NORTHCOTT.
